GRINDING MACHINE

John G. Thompson, Worcester, Mass., assignor
to Norton Company, Worcester, Mass., a cor-
poration of Massachusetts

Application October 30, 1937, Serial No. 171,924

1 Claim. (Cl. 51—95)

The invention relates to grinding machines, and with regard to its more specific features to a work head for imparting an eccentric motion to the work piece.

5 One object of the invention is to provide a cylindrical grinder adapted to grind bodies to an eccentric cylindrical contour. Another object of the invention is to provide a cylindrical grinder to grind elliptical bodies. Another object of the 10 invention is to provide a work head for grinding machines for the grinding of eccentric and elliptical bodies. Another object of the invention is to provide a machine or an attachment for grinding elliptical automotive pistons. Other objects will 15 be in part obvious or in part pointed out hereinafter.

The invention accordingly consists in the features of construction, combinations of elements and arrangements of parts, as will be exemplified 20 in the structure to be hereinafter described, and the scope of the application of which will be indicated in the following claim.

In the accompanying drawing in which is illustrated one of many possible embodiments of the 25 mechanical features of this invention,

Figure 1 is a front elevation of a grinding machine having the work head of the invention incorporated thereon;

Figure 2 is an end elevation of the work head, 30 certain parts being shown in a section taken on the line 2—2 of Figure 1;

Figure 3 is a horizontal axial sectional view taken on the line 3—3 of Figure 2; and

Figure 4 is a fragmentary vertical axial sectional view on an enlarged scale taken on the line 4—4 of Figure 2.

I provide a plain cylindrical grinder including, as shown in Figure 1, a base 10 supporting on the usual ways for longitudinal reciprocation a table 40 or carriage 11.

The machine may have the usual wheel head 20 journaling a shaft 21 upon which is mounted a grinding wheel 22. In such event there is preferably provided a motor 23 driving a pulley 24 45 which is connected by multiple belts 25 to a pulley 26 attached to shaft 21. The usual cross slide ways, not shown, for the wheel head 20 are also provided whereby to move the grinding wheel 22 toward and from the work piece.

50 For control of the cross feed there is provided a hand wheel 30 with a micrometer adjustment device 31 and a ratchet wheel, not shown, operated by a pawl 32 which is attached to a slide 33 operated by a connecting rod 34 eccentrically 55 attached to a disk 35. Connected to the disk 35

is a small gear, not shown, which meshes with a rack 37 on the end of an arm 38 which is connected at 39 to an arm 40 attached to the main reversing lever 41 which is positioned for contact with the usual table reversing dogs or stops 42 5 and 43 adjustably secured to the table or carriage 11. The reversing lever 41 operates a mechanical reversing mechanism, not shown, to reverse the table 11 first in one direction and then in the other, according to the position of the lever 10 41. By means of a hand lever 45 the direction of travel of the table 11 can be reversed manually. I provide further manually operated mechanism for moving the table or carriage 11 comprising a hand wheel 50 mounted on the shaft 51 which is 15 attached to pinion gear 52 meshing with a large gear 53 to which is attached a pinion gear 54 meshing with a rack 55 attached to the under side of the table or carriage 11. For the mechanism thus indicated, hydraulic driving and reversing mechanism may be substituted, if desired. For a fuller description of one form of grinding machine embodying many of the features heretofore indicated, reference may be had to patent to C. H. Norton No. 762,838 granted 25 June 14, 1904.

The work head 60 of the machine is mounted upon the table or carriage 11 which provides the usual ways 61, 61 to which the work head 60 may be clamped in any longitudinal position by means 30 of the overhanging portion 62 on one side and the clamp 63 on the other side, as shown in Figure 2. On the top of the work head 60 is mounted a motor 65 which, as better shown in Figure 1, has a pulley 66 on the armature shaft 67 thereof. 35 The pulley 66 is connected by a belt 68 to a pulley 69 mounted on a shaft 70 journalled in the work head. Referring now to Figure 3, a journal 71 is provided for the shaft 70 in the work head. Keyed to the shaft 70 are spur gears 72 and 73 40 of different diameters. The spur gear 72 meshes with a spur gear 74 which is keyed to an eccentric sleeve 75 journalled in journals 76 in the work head 60. The spur gear 73 meshes with a spur gear 80 which is mounted for rotation on a hub 45 81 of the gear 74, which hub is concentric with the axis of the gear 74.

The sizes of the gears 72, 73, 74 and 80 are such that the gear 74 is rotated at twice the angular velocity of gear 80. Referring now to Figures 2, 50 3 and 4, the gear 80 has an annular ridge 85 projecting from its surface, which ridge, however, has two slots 86 therein. A disk 87 has diametrically opposite projecting arms 88 which fit in the slots 86. The disk 87 is attached by 55

5 screws 89 to a sleeve 90 which is journalled in journals 91 in the sleeve 75. The journals 91 are, however, eccentrically located in the sleeve 75 and revolve with it. Thereby a rotating motion is given to the axis of the sleeve 90 as it revolves.

10 The work piece A to be ground is the piston of an automobile having a wrist pin bore B. I provide a long spindle 94 in the sleeve 90 which has a cross pin 95 in the front end which can be located in the bore B, as shown in Figure 3. The sleeve 90 has a screw threaded portion 96 upon which fits a driving plate 97 shaped to receive the lower end of the piston A. The left-hand end of the spindle 94 is threaded and receives a 15 hand wheel 100. By tightening the hand wheel, the pin 95 is drawn to the left against the bore B, so pressing the piston A against the plate 97.

20 It will be seen that the piston A can readily be mounted in position for rotation by the work head and removed therefrom, the latter by simply releasing the hand wheel 100 and pressing the pin 95 out of the bore B and the spindle 94. Whenever the motor 65 is energized with the work piece A in position to be operated upon, the 25 work piece A will be given such a motion that the grinding wheel 22, when brought against the work piece in the usual manner, will generate an elliptical surface thereon. From the standpoint of manufacture of an automobile, an elliptical 30 piston has certain advantages.

35 The journals 91 define the axis of the work piece which is constantly changing in position since the journals 91 are fixed in the sleeve 75. The work piece is thus revolved and its axis is revolved at the same time. Since the position of the grinding wheel is relatively fixed except for the small amount of feed the work piece is thus revolving and also approaching and receding from the grinding wheel. Since the gear 74 is 40 revolving at twice the speed of the gear 80 the work piece advances and retreats to and from the grinding wheel twice during each revolution

thereof. This will generate an elliptical surface on the work piece since considering the angular displacement of a point generating the circumference of an ellipse, it moves from and towards the center twice during a complete revolution. 5 Furthermore the angular velocity of approach and recession is accelerated according to the sine curve law.

It should be observed, however, that if the gears 72 and 73 be of equal diameter the axis of the work piece will approach and recede from the grinding wheel once for each revolution of the work piece and thus will generate an eccentric surface on the work piece. By a small change, therefore, in the gears in this apparatus an eccentric work piece may be generated. Other shapes 15 also may be created by still different gear ratios.

It will thus be seen that there has been provided by this invention apparatus in which the various objects hereinabove set forth together 20 with many thoroughly practical advantages are successfully achieved. As many possible embodiments may be made of the above invention and as many changes might be made in the embodiment above set forth, it is to be understood that 25 all matter hereinbefore set forth or shown in the accompanying drawing is to be interpreted as illustrative and not in a limiting sense.

I claim:

30 In a grinding machine, a table or carriage, a grinding wheel, means to move the grinding wheel toward and from the table or carriage, the table or carriage being movable parallel to the axis of the grinding wheel, and a work head comprising a support mounted on said table or carriage, a 35 sleeve journalled in said support, a work holder journalled in said sleeve, and means to rotate both of said sleeve and said work holder, one of said parts being eccentric with respect to another of 40 said parts.

JOHN G. THOMPSON.
